UNITED STATES PATENT OFFICE

2,377,404

AIRPLANE JACK

Floyd C. Cullers, Arcadia, Fla.

Application September 29, 1943, Serial No. 504,307

5 Claims. (Cl. 254—7)

The present invention relates to manually operated trucks adapted for supporting and moving airplanes into a desired location in a factory or hangar and has for an important object to provide jacking means carried by the truck for raising the front end of the airplane and supporting the same while being moved.

A further object is to provide means for simultaneously and uniformly raising both front landing wheels of the airplane for supporting the same in a balanced position on the truck.

Another object is to provide a device of this character of simple and practical construction, which is strong and durable, efficient and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings, wherein like numerals refer to like parts throughout, and in which

Figure 1 is a front elevational view.

Figure 2 is a longitudinal sectional view.

Figure 3 is a fragmentary top plan view, and

Figures 4, 5 and 6 are sectional views taken respectively on the lines 4—4, 5—5 and 6—6 of Figure 1.

Referring now to the drawings in detail wherein for the purpose of illustration I have disclosed a preferred embodiment of my invention, the numeral 5 designates a frame generally, which is formed of a pair of spaced parallel channel members 6 having their open sides opposed to each other and connected intermediate their ends by a cross member 7, and also connected at their ends by cross members 8 and 9 to the under side of the latter of which are mounted casters or swivel rollers 10. Braces 11 extend from the outer ends of the cross members 8 and 9 to the upper edges of the frame members 6.

An inverted U-shaped post 12 has its ends suitably secured to the outer sides of the frame members 6 and rises from said members with the upper end of the post flattened as shown at 13 and to which is bolted or otherwise secured a gear housing 14 having a bearing sleeve 15 projecting from one side thereof.

Bevel gears 16 and 17 are positioned in the housing in engaged relation, the gear 16 having a shaft 18 journaled in the sleeve 15 and provided at its outer end with a hand wheel 19. The gear 17 is secured on the upper end of a screw 20 which extends downwardly from the

housing through the upper end of the post and is journaled at its lower end in the cross member 7.

A carrier block 21 is threaded on the screw 20 for vertical movement and from the opposite sides of which project spaced pairs of ears 22 and 23 for pivotally attaching an end of a pair of lift arms 24 and 25 by pins 26 and 27. Each of the arms 24 and 25 include telescoping tube sections 28 and 29.

A pair of slides 30 and 31 extend transversely of the frame and having upstanding flanges 32 and 33 slidably fitted in the channels of the frame members 6. A pair of lugs 34 rise from each slide having a pin 36 on which one of the tubes 29 is pivoted adjacent its outer end.

The end of each tube 29 projects outwardly beyond the end of the frame and is formed with a vertical slot 37 in which is inserted a flat bar 38 having vertically spaced openings 39 for selectively receiving a pin 40 extending transversely of the tube to secure the bar 38 in vertically adjusted position. On the upper end of the bar 38 is a curved head 41 adapted to form a seat for an axle housing 42 of one of the front landing wheels 43 of an airplane, the axle housing at each side of the airplane resting on one of the heads at the outer end of each lift arm. The heads 41 are provided with recesses 41' to receive lugs (not shown) usually formed on the housings 42 to prevent slipping of the housings from the heads.

Accordingly in the operation of the device, the heads 41 are placed under the axle housings of the landing wheels and by manipulation of the hand wheel 19 in a proper direction the carrier block 21 is moved downwardly causing a lowering movement of the inner ends of the lift arms 24 and 25 and a raising movement of the outer ends of the arms whereby to lift the airplane and support it in an elevated position for transporting the same on the rollers 10. The airplane may thus be easily and quickly moved about on the truck into a desired position in the hangar or factory.

The slides 30 and 31 are adjustable in the channels of the frame to accommodate various types of machines having landing wheels spaced apart at different distances and also to compensate for variations which may occur in the distances between the wheels resulting from a flat tire.

It is believed the details of construction, operation and advantages of the device will be read-

ily understood from the foregoing without further detailed explanation.

Having thus described my invention, what I claim is:

1. A jack of the class described comprising an elongated wheel supported frame, a screw rising from the central portion of the frame and rotatably supported thereon, a carrier block mounted for vertical movement on the screw, a pair of arms pivoted at one end on the block and projecting oppositely therefrom, means pivotally and slidably supporting an intermediate portion of the arms on the frame adjacent the outer ends of the latter, means at the outer ends of the arms adapted to engage and support an object, and means for actuating the screw.

2. A jack of the class described comprising an elongated wheel supported frame, a screw rising from the central portion of the frame and rotatably supported thereon, a carrier block mounted for vertical movement on the screw, a pair of arms pivoted at one end on the block and projecting oppositely therefrom, slides carried by the frame to which the arms are pivoted at intermediate portions, means at the outer ends of the arms adapted to engage and support an object, and means for actuating the screw.

3. A jack of the class described comprising an elongated wheel supported frame, a screw rising from the central portion of the frame and rotatably supported thereon, a carrier block mounted for vertical movement on the screw, a pair of arms pivoted at one end on the block and project-

ing oppositely therefrom, slides carried by the frame to which the arms are pivoted at intermediate portions, means at the outer ends of the arms adapted to engage and support an object, and a hand wheel operatively connected to the screw for actuating the latter.

4. A jack of the class described comprising an elongated wheeled frame formed of a pair of channel members, cross members connecting the channel members in spaced parallel relation with the open side of the channel members arranged in opposed relation, a support rising from the frame, a vertical screw rotatably carried by the support, a carrier block arranged to travel on the screw, a pair of arms pivoted at one end to the block, slides having end portions positioned in the respective channel members and to which the arms are pivoted adjacent the outer ends of the latter, means at the outer ends of the arms adapted for engaging and supporting an object, and means for manually operating the screw.

5. A jack for the landing wheels of an airplane and comprising an elongated frame, a pair of slides on opposite ends of the frame, a pair of lifting arms each including an inner section and a longitudinally slidabile outer section pivotally attached to one of the slides with the outer end of said sections adapted for engaging a part of the landing wheels, and operating means for the inner sections of the arms adapted to simultaneously and uniformly actuate the arms.

FLOYD C. CULLERS.
